UNITED STATES PATENT OFFICE

HARRY L. BAKER, OF ELMIRA, NEW YORK

DISPLAY CABINET

Application filed July 31, 1928. Serial No. 296,479.

This invention relates to certain new and useful improvements in display cabinets and more particularly to a type of cabinet showing greeting cards and the like, the cabinet comprising a multi-leafed cover section for displaying various kinds of cards with an appropriate classification and price notation for cards indexed in the cabinet.

A further object of the invention is to provide in a display cabinet of the above type, a novel form of cover that comprises hinged sections with the free edge of the lower part of the hinged cover sections being hinged to the cabinet body in a manner to permit the upper cover section to be raised for the display of greeting cards and the like upon opposed faces of the sections, with the lower cover section remaining in closing engagement with the open upper end of the cabinet.

A still further object of the invention is to provide a relatively short hinged leaf between the two hinged cover sections for the further display of greeting cards and the like upon both sides thereof, all of the greeting cards being hidden from view when the two cover sections are closed, while the classified stock of greeting cards placed in the cabinet hidden from view and protected from outside elements when the upper cover section alone is raised.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a perspective view of a greeting card display cabinet constructed in accordance with the present invention, the cover section for the cabinet being entirely closed;

Figure 2 is a perspective view of the display cabinet with the upper section of the cover raised and limited in such movement by the tapes extending between the sections of the cover, the relatively shorter intermediate section of the cover being lowered, and showing the greeting cards on display;

Figure 3 is a perspective view, similar to

Figure 2 showing the smaller intermediate section of the cover elevated;

Figure 4 is a perspective view of the cabinet with all of the sections of the cover partly elevated to show the indexed classification of cards in the compartments in the cabinet;

Figure 5 is a vertical longitudinal sectional view taken through the cabinet; and

Figure 6 is a vertical cross-sectional view showing all of the cover sections raised to elevated positions and further showing, by dotted lines, the upper section of the cover elevated or opened.

The display cabinet disclosed in this application is illustrated as being of rectangular form comprising a bottom wall 1, front and rear walls 2 and 3 respectively, end walls 4 and 5 and a cover section 6 comprising a plurality of leaves hinged to the upper edge of the rear wall 3 as at 7.

The cover section 6 comprises a pair of cover walls 8 and 9, the cover wall 8 having the hinged connection 7 with the rear wall 3 of the cabinet, while the other edge of the cover wall 8 is hinged as at 10 to the cover wall 9. An intermediate display leaf 11 is smaller than the cover walls 8 and 9, the display leaf 11 being included in the hinged connection 10 to assume positions relative to said cover walls in a manner to be described.

When the cover section 6 is in the closed position shown in Figure 1, the cover walls 8 and 9 and leaf 11 lie juxtaposed and form a closure for the open upper end of the cabinet.

The upper and lower faces of the cover walls 8 and 9 respectively have sample greeting cards or the like 12 suitably secured thereto, while both faces of the leaf 11 carry display cards.

The normal position of the display cabinet is illustrated in Figure 2 with the cover wall 9 opened and limited in such movement by the side tapes 13 extending between opposite ends of the cover wall 9 and the cover wall 8. The leaf 11 is illustrated as resting upon the closed cover wall 8 and may be raised to display the cards upon the other side thereof as shown in Figure 3. Each greeting card 12 has a poster 14 associated therewith bearing an index number and price notation, the cabinet containing an index and

classified arrangement of the cards corresponding to the pasters 14. To obtain access to the interior of the cabinet, the cover section 6 is fully opened as illustrated by full lines in Figure 6 and said cabinet is divided into compartments by the partitions 15. The greeting cards 16 and companion envelopes 16^a are located by the index cards 17 provided with data 14^a corresponding with the pasters 14. Opening movement of the cover section 6 is limited by the end tapes 18 extending between the cover wall 8 and the end walls 4 and 5 of the cabinet.

From the above detailed description of the invention, it is believed that the construction and operation thereof will at once be apparent, it being noted that the greeting cards or similar articles are capable of prominent display while the stock of cards for sale confined within the cabinet are fully protected from soiling by handling or the like. The additional fly leaf between the hinged walls of the cover sections provide for an increased display, while the pasters 14 associated with the displayed cards carry the index key to the classified subject matter in the cabinet.

While there is herein shown and described the preferred embodiment of the present invention, it is nevertheless to be understood that minor changes may be made therein without departing from the spirit and scope of the invention as claimed.

What I claim as new is:—

1. A display cabinet comprising a cabinet section, and a hinged cover section including a pair of hinged walls with display areas on the adjacent faces thereof.

2. A display cabinet comprising a cabinet section and a hinged cover section including a pair of hinged walls with display areas on the opposed faces thereof, and a display leaf hinged between the walls of the cover section.

3. A display cabinet comprising a cabinet section and a hinged cover section including a pair of hinged walls with display areas on the opposed faces thereof, means for limiting opening movement of the upper wall of the cover section, and a display leaf hinged between the walls of the cover section.

4. In a display cabinet wherein a cabinet body contains classified stock and a hinged cover for the cabinet body displaying samples of the stock and bearing reference to the stock, said hinged cover comprising a pair of upper and lower walls hinged together with an edge of the lower wall hinged to the cabinet body.

5. In a display cabinet wherein a cabinet body contains classified stock and a hinged cover for the cabinet body displaying samples of the stock and bearing reference to the stock, said hinged cover comprising a pair of walls hinged together at edges spaced from the hinge connection between the cover and

cabinet body, and a display leaf joined to the hinge connection between the cover walls.

6. A display cabinet comprising a cabinet body, and a cover section hinged thereto including hinged walls with the lower wall hinged to the body and opening in a direction reverse to the opening movement of the cover section whereby the cover walls may be separated and the cabinet body remain closed.

In testimony whereof I affix my signature.

HARRY L. BAKER.
